nolele.com website Dec. 20, 2024. Available at URL <https://nolele.com/> (Year: 2024).*Primary Examiner — Jennifer L Watkins
Assistant Examiner — Christine Tucci(57) **CLAIM**

The ornamental design for a swaddling garment as shown and described.

DESCRIPTION

FIG. 1 is a front view of a swaddling garment showing my new design;

FIG. 2 is a rear view of the swaddling garment;

FIG. 3 is a left side view of the swaddling garment;

FIG. 4 is a right side view of the swaddling garment;

FIG. 5 is a top view of the swaddling garment;

FIG. 6 is a bottom view of the swaddling garment; and,

FIG. 7 is a top front side perspective view of the swaddling garment.

The broken lines are illustrative of boundaries defining portions of the device forming no part of the claimed design.
